United States Patent

Des. 239,796
Patented May 11, 1976

239,796

DISPLAYER FOR A FINGER RING

John R. Williams, Indianapolis, Ind., assignor to Mahan Co. Inc., Indianapolis, Ind.

Filed June 28, 1974, Ser. No. 484,288

Term of patent 14 years

Int. Cl. D20—02

U.S. Cl. D6—85

Fig. 1

Fig. 2

FIG. 1 is a perspective view of a display for a finger ring, with a ring shown in dotted lines for illustrative purposes only in the display position.

FIG. 2 is a perspective view of the display device showing the holding clip in its proper position.

FIG. 3 is a side view of the display device of FIG. 2.

I claim:

The ornamental design for a display for a finger ring, as shown and described.
